UNITED STATES PATENT OFFICE.

EDWIN L. SHUTE, OF ANSONIA, ASSIGNOR TO JOHN E. EARLE, OF NEW HAVEN, CONNECTICUT.

ELECTRIC GAS-LIGHTER.

SPECIFICATION forming part of Letters Patent No. 295,059, dated March 11, 1884.

Application filed November 3, 1883. (No model.)

To all whom it may concern:

Be it known that I, EDWIN L. SHUTE, of Ansonia, in the county of New Haven and State of Connecticut, have invented a new 5 Improvement in Electric Gas-Lighters; and I do hereby declare the following, when taken in connection with accompanying drawings and the letters of reference marked thereon, to be a full, clear, and exact description of the 10 same, and which said drawings constitute part of this specification, and represent, in—

Figure 1, a side view; Fig. 2, a top or plan view; Fig. 3, a side view at right angles to Fig. 1; Fig. 4, the armatures in connection with 15 the gas-cock; Fig. 5, a modification; Fig. 3^a, the locking device as engaging the cock in the cut-off position.

This invention relates to an improvement in that class of automatic gas-lighters in which 20 an electro-magnet is connected at one end with the wire through which the current of electricity is passed, and at the other with a circuit-breaker at the gas-burner, and arranged so that the current of electricity is passed to 25 the circuit-breaker through said magnet, attracting an armature in connection with the gas-cock, whereby the gas is automatically turned on and lighted by the spark produced at the tip of the burner from said magnet in 30 the circuit, and in which, in some cases, a second magnet is arranged, the armature of which is also in connection with the gas-cock, and so that a current of electricity through said magnet will attract its armature and cut off the 35 gas.

Before referring to my improvement I will briefly describe the general construction.

A, Fig. 3, represents the gas-burner, attached to the gas-fixture by its socket B, in the usual 40 manner of attaching gas-burners. At one side of the burner is a magnet, C, over which an armature, D, is hung upon a pivot, a, and so as to swing up and down from and toward the poles of the magnet. From the pivot-point of 45 the armature D an arm, E, extends into connection with the gas-cock F, as seen in Fig. 4, and so that by turning the armature from the position seen in Fig. 3 to that seen in Fig. 4 the plug of the cock will be turned to open 50 the gasway, and the armature raised will turn the arm E in the opposite direction and cut

off the gas. Upon the side of the burner opposite the armature the circuit-breaker is arranged. This consists of two platinum or other suitable points, b d, so near the opening in the 55 gas-burner that a spark produced between them will ignite the gas. The one point, b, is fixed, say, as in a bracket, G, (see Fig. 1,) and is in connection by a wire, e, with the magnet C. The other point, d, is the termination of 60 an arm extending from a vertical rod, H, working through a socket, I, on the bracket G, and extends below the bracket, and is there provided with a spring, K, the action of which is to hold the point d down upon the point b, as 65 seen in Fig. 1. The armature-lever extends beyond its pivot, and so as to stand beneath the extreme lower end, f, of the rod I, and so that when the armature D is drawn down, as seen in broken lines, Fig. 3, the extension on the opposite side of the pivot will strike the lower end, f, of the rod H and raise that rod before the armature comes into contact with the core of the magnet to close the circuit. This movement 70 of the armature and rod H raises the point d 75 from the point b, forming an arc, and producing a spark to light the gas, which has been turned on by the movement of the armature, as before described. Immediately on the opening of the circuit, and which is done so soon 80 as the gas is lighted, the spring K forces the rod H downward and brings the points b d again into contact. The action of this spring, through the rod upon the armature, necessarily raises the armature, and consequently turns 85 the plug of the cock to the extent of such movement. The plug must necessarily work with great freedom. The armature being free, it frequently occurs that on the breaking of 90 the circuit the movement of the armature, under the action of the spring K, will be greater than desirable, and hence will cut off a considerable portion of the gas. Again, standing free, as it necessarily must, it is liable to movement under any jar or shock which may 95 accidentally be brought to the burner. Such jar or shock is frequently sufficient to entirely cut off the gas. Particularly is this the case where, as represented in the drawings, a second magnet, L, is arranged upon the opposite 100 side to the magnet C, the armature-lever extended across and carrying at its opposite end

the armature M of the magnet L, the armature M substantially counterbalancing the armature D. The magnet L is employed to extinguish the gas. This is done by closing the 5 circuit and bringing the armature M upon the pole of the magnet, as seen in Fig. 3, the circuit being opened so soon as the gas is extinguished, it being understood that this device is worked on an open circuit. The same difficulty which I have described as existing in 10 the liability of the gas being cut off exists in the liability of the gas-cock to be opened when once it has been extinguished.

The object of my invention is to overcome 15 these difficulties; and it consists in a locking device in connection with the armature-lever, whereby when the gas-cock is opened the armature will be locked in that position, and released from such lock when the circuit is closed 20 for the purpose of cutting off the gas, and also in a like locking mechanism in connection 25 with the armature, so as to lock the armature in the cut-off position, such lock being opened by the closing of the circuit, which opens the gas-cock, and as more fully hereinafter 30 described. On the axis upon which the armatures turn I arrange a disk, N, in the periphery of which is a notch, h, or it may be simply an arm extending from the axis, in the 35 end of which the notch h is formed.

i is a dog hung upon a spring, P, the nose of the dog arranged to engage the notch h when the armature D is drawn down to open the supply of gas. Upon this dog is an armature, l, and beneath it is a magnet, R, the core 35 m in such relative position to the armature l that when the circuit through the magnet R is closed it will attract the armature and draw the dog from its engagement with the notch 40 h. This magnet R is in connection with the magnet L, so that when the circuit through the magnet L is closed to attract the armature M the magnet R will attract its armature and draw the dog i from the notch h.

45 Suppose the parts to be in the position of gas cut off, as seen in Fig. 3, the circuits open. To light the gas, the circuit through the magnet C is closed, which causes its armature D, as before described, to let on the gas and produce the spark. As the armature D approaches its magnet, the nose of the dog i falls into the notch h, and locks the armature in that position, so that accidental turning of the gas-cock is impossible. When the gas is 55 to be extinguished, the circuit through the magnets L and R is closed, the first action of such closing being that the magnet R will attract its armature l and draw the dog i from its locking engagement with the notch h; then 60 the armature, being free to turn, is brought into contact with the magnet L, and the gas

cut off. To lock the armature or armature-lever in its cut-off condition, a like disk, N', is arranged upon the opposite end of the axis of the armature, and a like magnet, R', arranged 65 in connection with the circuit through the magnet C. A like dog, i', is arranged to engage a like notch, h', (see Fig. 3a,) and so that when the circuit through the magnet C is closed to let on the supply of gas the dog i' 70 will be first drawn from its engagement with the notch h', thus leaving the armature D free to be drawn to its magnet and open the supply. This locking mechanism for the armatures may be applied to other and similar gas- 75 lighting apparatus. I therefore do not wish to be understood as limiting this locking apparatus to the precise arrangement of magnets, armatures, and circuit-breaker shown.

It will be readily seen that the dog may be 80 applied to the gas-cock directly, and produce the same result, say, as seen in Fig. 5. Therefore, while I prefer to apply this locking device to the axis of the armatures, I do not wish to be understood as limiting my invention 85 to that particular arrangement.

I claim—

1. In an electric gas-lighting apparatus, the combination of the gas cock and burner, two magnets—one in connection with the circuit 90 for opening the supply of gas, the other in connection with the circuit for cutting off the supply of gas—the armatures of said magnets in connection with the gas-cock, the magnet R in connection with the magnet for cutting off 95 the supply of gas, and a spring-dog arranged to automatically lock the gas-cock in its open position, said dog attached to or made a part of the armature of said magnet R, and whereby said dog will be released from its engagement upon the closing of the circuit for cutting off the gas, substantially as described.

2. In an electric gas-lighting apparatus, the combination of the gas cock and burner, two magnets—one in connection with the circuit 105 for opening the supply of gas, the other in connection with the circuit for cutting off the supply of gas—the armatures of said magnets in connection with the gas-cock, the magnet R' in connection with the magnet for opening 110 the supply of gas, and a spring-dog arranged to automatically lock the gas-cock in its closed position, said dog attached to or made a part of the armature of said magnet R', whereby said dog will be released from its engagement 115 upon the closing of the circuit for letting on and lighting the gas, substantially as described.

EDWIN L. SHUTE.
